The Hartman-Holm Co., Norwood, Ohio, a cor-
poration of Ohio

Application November 2, 1949, Serial No. 5,830

Term of patent 14 years

(Cl. D34—15)

To all whom it may concern:

Be it known that I, Clarence F. Hartman, a citizen of the United States, residing at Silverton, in the county of Hamilton and State of Ohio, have invented a new, original, and ornamental Design for a Toy Ring-Launching Device, of which the following is a specification, reference being had to the accompanying drawings, forming part thereof.

Fig. 1 is a side view of a toy ring-launching device showing my new design.

Fig. 2 is a top view of the device of Fig. 1.

Fig. 3 is a forward end elevational view of the device of Fig. 1.

Fig. 4 is a rear elevational end view of the device of Fig. 1.

I claim:

The ornamental design for a toy ring-launching device, as shown.

CLARENCE F. HARTMAN.
